United States Patent Office

Des. 220,821
Patented May 25, 1971

220,821

PORTABLE RADIO

Maurice D. Katz, 35 Broadway, Lawrence, N.Y. 11559

Filed Dec. 3, 1970, Ser. No. 26,272

Term of patent 14 years

Int. Cl. D14—03

U.S. Cl. D56—4

FIG.1.

FIG.2.

FIG. 1 is a front, top and right side perspective view of a portable radio, showing my new design; and

FIG. 2 is a rear, top and left side perspective view thereof.

Portions of the drawing figures are shaded to indicate contrast in appearance.

I claim:

The ornamental design for a portable radio, substantially as shown and described.
